CLAIM

The ornamental design for a watercraft rail mount, as shown and described.

DESCRIPTION

FIG. 1 is a first isometric view of a watercraft rail mount showing our new design;

FIG. 2 is a second isometric view thereof;

FIG. 3 is a front view thereof;

FIG. 4 is a back view thereof;

FIG. 5 is a top view thereof;

FIG. 6 is a bottom view thereof;

FIG. 7 is a first side view thereof; and,

FIG. 8 is a second side view thereof.

The broken line portion of the figures is included to show unclaimed subject matter only and forms no part of the claimed designs.
